UNITED STATES PATENT OFFICE.

JOSEPH D. HORTON, OF FORT SMITH, ARKANSAS.

PORTABLE HOUSE.

No. 865,590.

Specification of Letters Patent.

Patented Sept. 10, 1907.

Application filed November 16, 1905. Serial No. 287,597.

To all whom it may concern:

Be it known that I, JOSEPH D. HORTON, a citizen of the United States, residing at Fort Smith, in the county of Sebastian and State of Arkansas, have invented certain new and useful Improvements in Portable Houses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to portable houses and has for its object to provide a structure of this class which can be erected without the use of tools, other than a wrench, screw-driver and hammer, and which does not require the services of a mechanic in order to erect or take down the same.

A further object of my invention is to provide a portable house which is particularly strong and substantial, and which is not liable to collapse and which will not deteriorate any quicker than houses ordinarily built.

A further object of my invention is to provide a portable house which may be employed for any and every purpose that a strong and thoroughly water tight structure is required.

With these objects in view, my invention consists in the novel construction of the parts forming the house, and in certain novel details which will be first fully described and afterwards specifically pointed out in the appended claims.

Referring to the accompanying drawings. Figure 1 is a vertical transverse section through the house. Fig. 2 is a perspective view showing two rafters and construction for tying same. Fig. 3 is a vertical longitudinal section through house. Fig. 4 is a perspective view of sills and girder. Fig. 5 is a horizontal section through house. Fig. 6 is a perspective view of one of the solid side sections or panels, and Fig. 7 is a fragmentary view showing a portion of floor of house.

Like numerals of reference indicate the same parts throughout the several figures in which:

1 indicates the sills which as shown in Figs. 1 and 3 are arranged over a suitable lattice work which lattice work is for the purpose of preventing fowls or animals from getting under the house. The sills are as shown in Fig. 4 fastened at their ends by slot and tenon construction, while the girders 2 are mortised into the sills as shown, no pins or bolts being employed.

The joist or floor beams 3 rest on the sills 1 as shown in Figs. 1 and 3, while the studs 4 are also set up on the sills 1.

5 indicates a strap anchor (Fig. 3) arranged on top of joist 3 and passes through lower end of stud 4 so as

to draw the parts firmly together. 6 indicates a sill plate arranged on the outside of the studs 4 and sill 1, through which sill plate the strap anchor also passes, and said sill plate is secured to the sill by a lag bolt 7. The sill plate 6 as shown, extends below the sill 1 and is secured to the lattice work by screws thus holding the lattice work firmly in position.

The studs 4 as shown in Figs. 5 and 7 are provided on either side with longitudinal grooves 8 to receive the side or wall sections 9. 10 indicates the horizontal wall plate which rests on the studs 4, said wall plate being also provided with longitudinal grooves 11 into which the side or wall sections 9 extend as shown in Fig. 7.

It will be seen in Fig. 1 that the roof cross-bars 12 are supported by the wall plates 10 and the rafters 13 are secured to the roof cross-bars.

14 indicates a truss hook which is secured to the underside of the roof cross-bars and is provided with a hooked end 15 which engages the wall plate 10.

16 indicates a stud plate which as shown in Fig. 1 is secured to the stud 4 while a bolt 17 passes through said stud plate, and roof cross-bar, thus securely tying the parts together. It will be noted that the rafter 13 extends below the roof cross-bar 12 and inside of the wall plate 10, while an anchor strap 18 passes through the stud 4 which draws said wall plate 10, against the rafter 13, thus forming a strong anchorage at intersection of wall and roof, preventing walls of building from being forced in by outside pressure.

Referring to the anchor strap 18 it will be seen that the end thereof is riveted to a piece of strap iron 19 which passes from one corner of the house to the other, said strap iron being arranged between the studs 4 and the wall plate 10, and can be coiled up in a compact space for transportation.

Referring particularly to Fig. 2 it will be seen that a short cross-bar 20 is provided near the upper end of the rafters 13 and that said cross-bar extends beyond the rafters. This construction is also illustrated in Fig. 1 and is for the purpose of forming a seat for the top cross batten 21 of the roof to hold said cross batten from slipping down. The roof boards 22 are secured to the cross battens 21 and said cross battens are fastened to the rafters, and a ridge timber 23 is arranged over the roof boards and is bolted down through the cross-bar 20 by a bolt 24 as shown in Fig. 1 thus securely binding the parts together and insuring a perfectly weather tight construction. If desired a chimney 25 may be provided which as shown in Fig. 3 is passed over a chimney collar 26, which collar is carried on a plate 27 which is slid under straps 28.

The floor and roof sections 29 are formed by nailing the floor or roof boards to cross battens 21, the ends of said battens being cut on a bevel so that the ends of the battens extend beyond the boards forming the sections.

When the sections are therefore placed together, the battens of one section lap over the boards of the adjacent section thus preventing any variation at the intersection of the sections and insuring a strong and substantial construction.

Referring now to Fig. 5 it will be seen that the window sash 30 is held in sliding position by a stop 31 vertically arranged in the studs 4, and by a stop 32 on the inner side of said studs. The studs at the door are also 10 provided with similar stops 33.

Referring now to Fig. 3, it will be seen that the porch 34 is anchored to the house by a short anchor strap 35 which passes through the side wall of the house, and also by a draw strap 36 which passes through the porch post 15 37 and through the side wall of the house. An angle strap 38 binds the porch roof 39 to the porch post 37, while the floor 40 of the porch is anchored to the posts and to the house sill 1 as shown.

What I claim as my invention, and desire to secure 20 by Letters Patent of the United States is:

1. In a portable house, the combination with the sill, of the floor joist and studs arranged thereon, a sill plate arranged on the outside of said sill and studs, means for fastening said sill plate to said sill and an anchor passing 25 entirely through the house and fastening said sill plate to said studs, substantially as described.
2. In a portable house, the combination with the studs, of a wall plate arranged on said studs, and a draw strap connecting the studs on opposite sides of the house, said 30 draw strap being interposed between the said studs and the said wall plate, substantially as described.
3. In a portable house, the combination with the rafters, of a lower cross-bar connecting the rafters together, the ends of said rafters extending below said cross-bar, studs 35 for said house, and a wall plate arranged on said studs, said wall plate being engaged by said extending ends of

said rafters to prevent said studs and wall plate from being forced inwardly, substantially as described.

4. In a portable house, the combination with the rafters, of a cross-bar therefor, studs supporting said rafters, a wall plate interposed between said studs and cross-bar, a truss-hook secured to said cross-bar and engaging the outside of said wall plate, and means passing through the roof covering and cross bar for tying the parts together, substantially as described.

45 5. In a portable house, the combination with the rafters, of a lower cross-bar therefor, a roofing carried on said rafters, studs supporting said rafters, means for anchoring said studs and rafters together, said means comprising also a fastening passing through said lower cross-bar and said roofing to securely tie the parts together at the intersection of the wall and roof of the house, substantially as described.

50 6. In a portable house, the combination with the rafters, of an upper cross-bar therefor, said upper truss extending beyond the edge of said rafters, a roof covering supported by said rafters and held against movement by the said upper cross-bar, substantially as described.

55 7. In a portable house, the combination with the rafters, of an upper cross-bar therefor, said upper cross-bar extending beyond the edge of said rafters, a roof covering arranged on a cross batten and carried on said rafters, said upper cross-bar forming a seat for said cross batten to hold said roof in position, substantially as described.

60 8. In a portable house, the combination with the rafters, of a cross-bar therefor, a roof covering on said rafters, a ridge timber arranged over said roof covering and a fastening means passing through said ridge timber, roof covering and rafter cross bar to tie the parts together, substantially as described.

65 70 In testimony whereof, I affix my signature, in presence of two witnesses.

JOSEPH D. HORTON.
